UNITED STATES PATENT OFFICE.

MILFORD T. VANDERVOORT, OF GRAND RAPIDS, MICHIGAN, ASSIGNOR TO WOLVERINE
BRASS WORKS, OF GRAND RAPIDS, MICHIGAN, A CORPORATION OF MICHIGAN.

AUTOMATIC CLOSING VALVE.

Application filed December 7, 1920. Serial No. 428,889.

To all whom it may concern:

Be it known that I, MILFORD T. VANDERVOORT, a citizen of the United States of America, residing at Grand Rapids, in the 5 county of Kent and State of Michigan, have invented certain new and useful Improvements in Automatic Closing Valves; and I do hereby declare the following to be a full, clear, and exact description of the invention, 10 such as will enable others skilled in the art to which it appertains to make and use the same.

This invention relates to an automatically closing valve of the same general type 15 closed in my Patent No. 1,302,104, issued April 29, 1919, having the same general appearance and worked, so far as the operator thereof is concerned, in the same manner, the construction interiorly being changed, 20 however, and operable on a different principle. In the present construction, it is designed that the closing of the valve shall be effected by the head of the liquid pressing on the valve, and at the same time a check 25 or brake interposed against such closing, the degree of such check being substantially in proportion to the head of water, the check or brake being automatically operated through a vacuum which is directly in proportion 30 to the speed of the passage of the water or similar liquid through the valve. It is a primary object and purpose of the invention to make an automatically operating valve which is controlled on the above described 35 principle. A further object of the invention is to make a valve of this character which is simple in construction, eliminating all springs therefrom, and one which is readily made and assembled at comparatively low 40 cost. Various other objects and purposes than those specifically stated will appear as understanding of the invention is had from the following description, taken in connection with the accompanying drawings, in 45 which,

Fig. 1 is a side elevation of the complete construction of closing valve.

Fig. 2 is a vertical section therethrough.

Fig. 3 is a fragmentary enlarged vertical 50 section through the upper part of the device showing the movable valve in upper liquid passing position.

Fig. 4 is a partial front elevation showing

the handle in its upper valve opening position.

Fig. 5 is a view looking against the vacuum brake operating lever, and

Fig. 6 is a transverse section through the lower portion of the device and at the air passages therethrough.

Like reference characters refer to like parts in the different figures of the drawings.

In the construction of the device, a hollow casing 1 is provided open at its lower and upper ends and an outlet pipe 2 is attached thereto at the lower end. An inlet coupling 3 is attached at the upper end of the casing, use being made of any well known type of connecting nut such as indicated at 4. The 5 fluid to pass through the casing may be carried to the coupling 3 through any suitable conduit such as a pipe screwed into the end of said coupling 3 and such fluid is usually under considerable head or pressure and 10 bears against the upper end of the closing valve set in the upper end of the casing.

In the construction of the valve, a sleeve 5 is used adjacent the upper end of which a leather 6 is secured, the same being adapted to bear in its lower position against an upwardly projecting annular rib 7 cast with the casing. A head 8 has a leather or like material washer 9 secured on its under side 15 which in lowermost position is adapted to bear against the upper end of the sleeve 5. The head 8 is attached to the upper end of a rod 10 extending downwardly through sleeve 5 and equipped with a cylindrical enlargement 11 at its lower end which bears 20 against a roller 12 rotatably mounted on an axis set off from the axis of a rod 13 which is rotatably mounted in and extends outwardly through a side of the casing as shown. A web 10^a is formed with the rod 10 and at its lower end has outwardly extending 25 projections 10^b coming under the lower end of sleeve 5. A handle 14 is attached to the outer end of the rod 13 and normally occupies the position shown in Figs. 1 and 2.

On turning the handle to substantially horizontal position, as shown in Fig. 4, the roller 12 serves to elevate rod 10 and attached head 8 and leather 9 above the sleeve 5, and as soon as projections 10^b are raised sufficiently 30 to engage with the lower end of sleeve 5, it

with the attached leather 6 is raised, as shown in Fig. 3. In the lower position of the valve parts, no liquid can pass by the valve, the greater the pressure of the liquid, 5 the tighter the valve will close, but as soon as the valve parts are raised, liquid will pass, the pressure of the liquid against the valve, however, tending to force the same to lower closing position and turn the rod 13 10 and attached handle 14 to original position. Rod 13 passes through and is rotatably mounted in a sleeve 15 threaded through a side of the casing 1. The outer end of the sleeve is slotted as at 15^a and a ring 16 15 having projections 16^a entering the slots is mounted on the rod 13 at the outer end of the sleeve. A washer 17 of leather or equivalent material is interposed between the ring 16 and the end of the handle 14. Pressure 20 on the ring transmitted to the washer serves to impose a friction brake against the return of the handle to lower position after it has been once raised.

A lever member 18 is associated with the 25 pressure ring 16, being divided at its upper end and formed with two inwardly turned arms 19 which enter the slots 15^a back of the projections 16^a on the ring 16. The lower end of the lever is vertically slotted at 20 30 making two spaced legs 21 against which an enlarged head 22 on the end of a rod 23 bears, the rod passing through the slot. The rod 23 extends inwardly and is connected at its inner end to a diaphragm 24 35 of flexible material which covers the outer side of an air compartment 25 made in the casing below the rod 13. A cylindrical cross member 26 connects the inner side of the compartment with the opposite side of the 40 casing, an opening being made lengthwise of the member 26 and opening at its inner end into the compartment 25 and at its outer end to the outside atmosphere. A plug 27 having a reduced opening 28 through it is 45 inserted into the outer end of the opening through member 26. An elbow 29 with an opening entirely through it is threaded into the opposite inner end of said member 26, the free end of the elbow being turned downwardly nearly to the bottom of the compartment 25. A pipe 30 is threaded at its 50 upper end through the lower side of member 26, the passage through the pipe communicating with the opening through member 26 as shown.

The lever 18 and associated mechanism is 55 covered by a sheet metal cover 31 attached to the casing by screws and serving to hold a reinforcing plate 32 against the edges of the diaphragm 24. The handle 14 has a projecting lug 33 which interposes a stop against the movement of the handle beyond horizontal position by coming against a stop lug 34 projecting into the path of 60 movement of lug 33.

In the operation, the handle is raised to horizontal position or until stopped by lug 34, this elevating the valve parts 5 and 8 and permitting the passage of liquid through the casing and out at the outlet 2. 70 The pressure of the liquid on the valve parts serves to tend to force them to closed position and return the handle to lower position. As soon as the handle is freed, it will begin to move to lower position. The passage of the liquid by the pipe 30 draws air through said pipe which is supplied from the outside through opening 28 and from the chamber 25. As passage 28 is small, the air will be 80 more or less exhausted from the compartment 25 and the pressure against the outer side of the diaphragm will cause it to be pressed inwardly, thereby acting on lever 18 to force the brake washer against the end of handle 14 and check the return movement 85 of the handle. The greater the pressure of water tending to close the valves, the greater the velocity will be past the pipe 30 and the greater the vacuum in compartment 25 and 90 brake pressure on the handle. Accordingly, it will be seen that there is a compensating action in the valve closing operation and that the valve will not close too quickly by reason of too heavy pressure against the valve parts, a greater or less check being 95 interposed in proportion to a greater or less pressure against the valve parts. The opening through the plug 27 may be made greater or less so as to have the brake action controlled properly to permit the return of 100 the handle and valve parts to lower position only after a desired amount of the liquid has passed.

The construction is relatively simple, 105 easily manufactured, has no parts to get out of order, and is automatic in its action. No springs liable to corrode are incorporated in the device. This makes the construction very durable in service. Many changes in minor detail of construction may be resorted to without departing from the principle 110 of the invention. The invention is defined in the appended claims and I consider myself entitled to all forms or modifications in structure that come within the scope of the 115 appended claims defining the invention.

I claim:

1. In a construction of the character described, a casing through which liquids may pass, a valve in the casing movable to two different positions, one an open position permitting the passage of liquids and the other a closed position preventing such passage, means for manually moving the valve to open position, said means tending to return to its normal position as soon as released, a 120 brake acting on said means to interpose a check against too rapid return, whereby the valve is checked in its return from open to closed position, and means automatically 125 130

acting to operate the brake to make the same of greater or less effectiveness in accordance with the greater or less pressure of the liquid passing through the casing.

5 2. In a construction of the character described, a casing through which liquids may pass, a valve in the casing movably mounted to occupy two different positions, one preventing the passage of liquid through the 10 casing and the other permitting such passage, means for manually moving the valve from said first position to allow the passage of liquid, said manually movable means tending to return to original position from 15 pressure of the liquid on the valve, a brake acting on the manually movable means, and means acting to set the brake against the handle, said means being rendered effective by the passage of liquid through the casing 20 and increasing with the increasing velocity of passage of the liquid.

3. In a construction of the character described, a casing through which liquids are adapted to pass, a valve movably mounted 25 in the casing to take two different positions, one a closed position preventing the passage of liquid and the other an open position permitting the passage of liquid, said valve being normally held closed by pressure of 30 the liquid against it, manually operated means for moving the valve to open position, a brake arranged to act against said manually operated means, a diaphragm covering an enclosed air chamber in the casing, 35 means connected to the diaphragm and operatively associated with the brake for setting the brake against the manually operated means on movement of the diaphragm into the air chamber, and means operated 40 by the passage of liquid thereby for exhausting air from the chamber and moving said diaphragm to set the brake.

4. In a construction of the character described, a casing through which liquids are 45 adapted to pass, a valve movably mounted in the casing to take two different positions, one a closed position preventing the passage of liquid and the other an open position permitting the passage of liquid, said valve being 50 normally held closed by the pressure of liquid against it, a manually operated handle, means operated by the handle for moving the valve to open position, a brake arranged to act against the handle, a diaphragm covering an enclosed air chamber in 55 the casing, means connected to the diaphragm and operatively associated with the brake for setting the same against the handle on movement of the diaphragm into the 60 air chamber, and an outlet conduit to the

air chamber extending downwardly in the casing and by which the liquid passes whereby air is drawn from the air chamber and the diaphragm moved to set the brake 65 against the handle and check its return to valve closing position.

5. In a construction of the character described, a casing through which liquids may pass, a valve in the casing movably mounted 70 to occupy two different positions, one a closed position preventing the passage of liquids, and the other an open position allowing such passage, said valve being normally held in closed position by the pressure 75 of liquid against it, a manually operated handle, means actuated by the handle and associated with the valve to move the valve from closed to open position on turning the handle to upper position, a brake associated 80 with the handle, said brake being normally ineffective, a diaphragm covering an enclosed air chamber in the casing, means connected to the diaphragm and operatively associated with the brake to press the brake 85 against the handle on movement of the diaphragm into the air chamber, a member formed with the casing between the inner side of the air chamber and the opposed side of the casing, said member having an opening therethrough, a plug having a reduced opening through it inserted in the outer end of the opening in said member, an elbow having a passage therethrough inserted into the inner end of said opening through the 90 member, said elbow extending downwardly 95 member, said elbow extending downwardly into the air chamber, and a pipe inserted through the under side of said member, said pipe having a passage therethrough communicating with the opening through said 100 member, substantially as and for the purposes described.

6. In a construction of the character described, a casing through which liquids are adapted to pass, a valve in the casing 105 mounted to take a closed position preventing the passage of liquids, or an open position permitting such passage, said valve being normally held in closed position by the pressure of liquid against it, means for manually moving the valve to open position, and means frictionally retarding the movement of the valve to closed position, the friction of said means being progressively increased in proportion to the velocity of passage of 110 liquid through the casing and in proportion to the pressure of the liquid against the valve tending to close the same.

In testimony whereof I affix my signature.

MILFORD T. VANDERVOORT.
